UNITED STATES PATENT OFFICE.

ANTONIO BOMMARITO, OF ST. LOUIS, MISSOURI.

ACETYLENE-LAMP.

1,220,940.

Specification of Letters Patent. Patented Mar. 27, 1917.

Application filed August 17, 1915. Serial No. 45,944.

To all whom it may concern:

Be it known that I, ANTONIO BOMMARITO, a citizen of Italy, residing at St. Louis, in the State of Missouri, have invented new 5 and useful Improvements in Acetylene-Lamps, of which the following is a specification.

The invention relates to miners' lamps, and more particularly to the class of acet- 10 ylene lamps for use by miners.

The primary object of the invention is the provision of a lamp of this character wherein the water contained within the water reservoir can be forced into the carbid holder 15 of the lamp in event that the communication between the two becomes clogged or choked, the water reservoir being of novel construction and containing an inflatable member which serves to exert pressure upon the wa- 20 ter for the proper feeding thereof to the carbid holder.

Another object of the invention is the provision of a lamp of this character wherein the water from the reservoir to the carbid holder can be regulated at will, thereby 25 controlling the flame from the lamp when lighted.

A further object of the invention is the provision of a lamp of this character where- 30 in the acetylene gas, prior to its consumption at the burner tip, is purified or cleaned for the production of an even flame and to avoid the clogging of the burner tip from sediment, incident to particles in the gas.

A still further object of the invention is the provision of a lamp of this character which is simple in construction, thoroughly 35 reliable and efficient in operation and inexpensive in manufacture.

With these and other objects in view, the invention consists in the construction, combination and arrangement of parts as will be hereinafter fully described, illustrated in the accompanying drawing, and pointed out 40 in the claims hereunto appended.

In the drawing:

Figure 1 is a front elevation of a lamp constructed in accordance with the invention;

Fig. 2 is a top plan view thereof;

Fig. 3 is a vertical longitudinal sectional view;

Fig. 4 is a sectional view on the line 4—4 in Fig. 2; and

Fig. 5 is a sectional view on the line 5—5

of Fig. 3 and looking in the direction of the arrows.

Similar reference characters denote corresponding parts in all the views throughout the drawings.

Referring to the drawings in detail, the lamp comprises a body A including an upper water reservoir 5 and a bottom carbid holder 6, the lower end portion or bottom of the water reservoir 5 being externally 60 screw threaded, as at 7, while the upper or open end of the carbid holder 6 is likewise screw threaded at 8 so that the reservoir and holder can be detachably connected with each other. Detachably threaded on the upper end of the water reservoir 5 and closing the same is a cover 9 which is formed with a central air inlet nipple 10 which communicates with the interior of an inflatable bag 11 mounted interiorly of the cover 9 65 and adapted to extend within the water reservoir 5 when the cover is fastened thereon, the nipple being fitted at its outer end with a detachable cap 12 provided with a central air inlet vent 13 so that air from the atmosphere will be admitted to the interior of the inflatable bag 11 for the expanding thereof. The bag 11 is molded or otherwise constructed of the form shown, that is, having a cylindrical wall which is adapted to fit 70 within the reservoir 5, and having outwardly curved or convex ends, and in its operative position one of such ends is forced inwardly, as illustrated in Figs. 3 and 4, to partly 75 expel the air from the interior of the bag. 75 The bag is of normal spherical shape and when in place the sides are held against expansion by the sides of the water reservoir 5. It is obvious that either section of the bag which, when in position, constitutes the 80 end may be pressed inwardly as shown. The bag is utilized by removing the cap 12 from the nipple 10 to provide a large vent and then compressing one portion of the bag 85 within the other by hand, holding the parts 90 in this position and reapplying the cap 12 to materially reduce the size of the vent. The cover 9 is then applied to the reservoir 95 5 and as the water is gradually used therefrom the vent 13 will admit a small amount 100 of air into the bag 5 so that it will gradually expand as the water is withdrawn from the reservoir in order that the normal elasticity of the bag will act with such inherent 105 force upon the body of water to induce more 110

or less pressure to force the water to the point of use.

Formed on the bottom of the water reservoir 5 centrally thereof is a water feed tube 14 and concentrically disposed with respect to the same and integral with the said bottom of the reservoir 5 is a reticulated or perforated cage 15 which forms a guard for the water tube 14 so as to prevent carbid within the holder 6 from being forced into the feed tube 14 and thereby obviate interference with the feed of the water from the reservoir 5 to the carbid holder 6 of the lamp.

Arranged interiorly of the water reservoir 5 is a semi-circular or hopper shaped false bottom 16 to provide a gas circulating space 17 which is filled with wool or other fibrous substance 18 serving as a filter for the gas admitted to the chamber 17 from the carbid holder 6, the bottom of the reservoir 5 being formed eccentrically with respect to the water feed tube 14 and cage 15 with a hole 19 which establishes communication between the said carbid holder 6 and the gas circulating space 17 so that the gas produced within the lamp can readily flow to the burner 20 which projects outwardly from the body A of the lamp and is in direct communication with the space 17 and carries a burner tip 21 of the ordinary well known construction and also a reflector 22 which is of the usual construction.

It is of course understood that the false bottom 16 has direct communication with the feed tube 14 so that the water from the reservoir 5 will flow into the feed tube and thence into the carbid holder 16 for mixing with the carbid therein to produce gas.

Formed on the water reservoir 5 is a valve guide sleeve 23 in which is threaded a needle valve 24, the same being diagonally disposed and adapted to control the feed passage in the water tube 14 for regulating the feed of water from the reservoir to the carbid container, the needle valve 23 being formed at its outer end with a peripheral knurled head 25 so that it can be actuated by hand in a convenient manner.

The cover 9 is formed with a corrugated or fluted external flange 26 which permits the convenient application of the cover or its removal from the reservoir 5 at will.

The jointed end of the water reservoir 5 and carbid holder 6 are formed with external annular flanges 27, between which is arranged a rubber gasket 28 to form a tight joint between the said reservoir and carbid container.

The inflatable bag 11 serves to force the water from the reservoir 5 into the container 6 and thereby assure a positive feed and thus make it possible to assure the feed of the water in event of the choking of the feed pipe 14 during the use of the lamp.

From the foregoing it is thought that the construction and manner of operation of the device will be understood and, therefore, a more extended explanation has been omitted.

Having thus described my invention, I claim:

1. A lamp of the class described comprising a water reservoir, a carbid container detachably connected with the reservoir, a water feed tube on the reservoir and extended within the container, a reticulated cage for the water feed tube, means for controlling the feed of water from the reservoir to the container, a removable cap for the reservoir, and an inflatable bag mounted in the cap completely closed against water and adapted to exert pressure upon the surface of the water within the reservoir for effecting a force feed thereof to the container. 70 80 85

2. A lamp of the class described comprising a water reservoir, a carbid container detachably connected with the reservoir, a water feed tube on the reservoir and extended within the container, a reticulated cage for the water feed tube, means for controlling the feed of water from the reservoir to the container, a removable cap for the reservoir, an inflatable bag mounted in the cap completely closed against water and adapted to exert pressure upon the surface of the water in the reservoir for effecting a force feed thereof to the container, means on the cap for admitting air to the bag from the atmosphere, and a vent cap detachably mounted on said means. 90 95 100

3. A lamp of the class described comprising a water reservoir, a carbid container detachably connected with the reservoir, a water feed tube on the reservoir and extended within the container, a reticulated cage for the water feed tube, means for controlling the feed of water from the reservoir to the container, a removable cap for the reservoir, an inflatable bag mounted in the cap completely closed against water and adapted to exert pressure upon the surface of the water within the reservoir for effecting a force feed thereof to the container, means on the cap for admitting air to the bag from the atmosphere, a vent cap detachably mounted on said means, and a burner tube for admitting gas from the carbid container. 105 110 115

4. A lamp of the class described comprising a water reservoir, a carbid container detachably connected with the reservoir, a water feed tube on the reservoir and extended within the container, a reticulated cage for the water feed tube, means for controlling the feed of water from the reservoir to the container, a removable cap for the reservoir, an inflatable bag mounted in the cap completely closed against water and adapted to exert pressure upon the water within the reservoir for effecting a force 120 125 130

feed thereof to the container, means on the cap for admitting air to the bag from the atmosphere, a vent cap detachably mounted on said means, a burner tube for admitting gas from the carbid container, and a false bottom in the reservoir and forming a gas circulating space between it and the bottom of the reservoir.

5. A lamp of the class described comprising a water reservoir, a carbid container detachably connected with the reservoir, a water feed tube on the reservoir and extended within the container, a reticulated cage for the water feed tube, means for controlling the feed of water from the reservoir to the container, a removable cap for the reservoir, an inflatable bag mounted in the cap completely closed against water and adapted to exert pressure upon the water

within the reservoir for effecting a force feed thereof to the container, means on the cap for admitting air to the bag from the atmosphere, a vent cap detachably mounted on said means, a burner tube for admitting gas from the carbid container, a false bottom in the reservoir and forming a gas circulating space between it and the bottom of the reservoir, and a wool packing within said gas space, the bottom of the said reservoir being provided with a hole for admitting gas from the container to the gas space.

20 25 30
In testimony whereof I affix my signature in presence of two witnesses.

ANTONIO BOMMARITO.
